UNITED STATES PATENT OFFICE.

THOMAS H. BATES AND ALBERT O. QUIMBY, OF FRESNO, CALIFORNIA.

DESIGN FOR A SPOON.

SPECIFICATION forming part of Design No. 21,952, dated November 1, 1892.

Application filed August 6, 1892. Serial No. 442,390. Term of patent 3½ years.

To all whom it may concern:

Be it known that we, THOMAS H. BATES and ALBERT O. QUIMBY, of Fresno, in the county of Fresno and State of California, have invented and produced a new and original Design for Spoons, of which the following is a description.

Reference is to be had to the accompanying drawing, forming a part of this specification, in which the figure represents the face view of a spoon embodying our new design.

The leading feature of our design consists in the representation of the hemispheres a a' on the handle, the said figures being joined

by an intermediate figure b , representing clasped hands. At one side of the clasped hands appear the representations of caravels. In the bowl of the spoon appears a bird's-eye view of the Columbian Exposition building.

We claim—

The design for a spoon herein shown and described.

THOS. H. BATES.
ALBERT O. QUIMBY.
